UNITED STATES PATENT OFFICE

BERNARD J. BOECKERMANN, OF DAYTON, OHIO, ASSIGNOR, BY MESNE ASSIGNMENTS, TO THE CAPPEL UPHOLSTERING COMPANY, OF DAYTON, OHIO, A CORPORATION OF OHIO

RESILIENT FURNITURE SLAT SUPPORT

Application filed May 7, 1930. Serial No. 450,513.

This invention relates to new and useful improvements in resilient furniture slat supports.

It is the principal object of my invention 5 to provide for upholstered furniture such as chairs and davenport, bottom slats that are hingedly secured at their front ends to the chair frame and which are supported at their rear ends by vertical helical springs attached 10 to said frame. These helical springs connected between the rear ends of the slats and the chair frame at points above them, allow a free vertical movement of the slats within the elastic limits of the springs, thereby providing 15 an extremely resilient seat where the weight is greatest. Such a seat is most beneficial to the occupant, and the helical springs never permit it to become solid.

Another object of the invention is to eliminate the webbing commonly used to support the springs of upholstered furniture.

Other important and incidental objects will be brought out in the following specification and particularly set forth in the subjoined claims.

In the accompanying drawing illustrating my invention, Figure 1 is a sectional view through the frame of a conventional upholstered chair. Figure 2 is a bottom view of the frame of the same. And Figure 3 is a detail view of my spring suspension means for the slat bottom of the chair.

Referring to the accompanying drawing for a detailed description of my invention, the numeral 1 designates an upholstered living room chair having bottom side rails 2, 2 and end rails 3, 3, that form a bottom frame to which short legs 4 are secured. The numeral 5 designates the back and 6 the arm rest of the chair. (See Figure 1.)

In Figure 1 the numeral 7 designates a seat cushion which is supported by a fabric bottom 8 connected between the end members 3, 3. This fabric bottom 8 rests upon the usual cushion supporting springs 9, of which nine are shown. The outer ones of these springs 9 are secured at their top portions to a square steel-wire frame 10.

The bottom portions of the cushion springs 50 9 are resiliently supported by slats 11. These

slats are supported at their front ends by spring angle clips 12 whose horizontal portions are secured to the bottom surfaces of the slats by nails 13 or other suitable fastening elements. The vertical parts of these angle clips are nailed or otherwise firmly secured to the front end rail 3 of the chair. Secured to the front end rails 3, a short distance above the front ends of the slats 11, is a horizontal member 14 that acts as a stop 55 to prevent damage to these slats, if they are moved inwardly during the packing of the chair.

The free or rear ends of the slats 11 are supported in the following manner to permit 60 them to yield most at those points where the weight which they support is the greatest. Attached to the bottom surfaces of the rear ends of the slats 11 by nails 15 or other suitable fastening elements, are spring angle 65 clips 16 having upwardly inclined portions that are apertured to receive the hook ends of helical springs 17. The upper hook ends of these springs are received by the inner downwardly inclined apertured ends of 70 spring clips 18 that are attached to the top parts of the rear end rails 3 by nails 19 or other suitable fastening elements.

When a downward pressure is exerted upon the rear ends of the slats 11, by the greater 75 weight which the occupant imposes upon the rear part of the cushion 7, they will yield within the elastic limits of the helical springs 17. A support of great resiliency is thus afforded by these slats with no fixed members 80 below to be engaged by them when a person is being seated in the chair, nor will they become a solid support through long and intensive use.

Hingedly secured at their front ends to the 85 front rail 3 and free to move vertically at their rear ends within the elastic limits of the helical springs 17, the slats 11 are an extremely yielding support for the cushion springs 9 upon which the cushion 7 rests. Under the 90 front end of this cushion a padding 18 is placed upon the fabric bottom 8.

Having described my invention, I claim:

1. In an article of the type described, the combination with a pair of end rails, of slats 100

horizontally disposed between and below the tops of said rails, spring angle clips for securing the front ends of said slats to the front end rail, and helical springs secured to the rear ends of said slats and inclining upwardly for attachment to the rear end rail to resiliently support the slats.

2. In an article of the type described, the combination with a pair of end rails, of slats horizontally disposed between said rails and below the tops thereof, means for securing the front ends of said slats to the front end rail, spring angle clips secured over the top of the rear end rail and having downwardly inclined inner end portions, spring angle clips secured to the bottom portions of the rear ends of the slats and having upwardly inclined rear end portions, and long inclined coil springs secured between the inclined ends of the spring clips.

In testimony whereof I have hereunto set my hand this 6th day of May, 1930.

BERNARD J. BOECKERMANN.
